UNITED STATES PATENT OFFICE.

RICHARD FINCKEN, OF SAN FRANCISCO, CALIFORNIA.

BEER-COOLING DEVICE.

No. 833,452.

Specification of Letters Patent.

Patented Oct. 16, 1906.

Application filed September 14, 1905. Serial No. 278,382.

To all whom it may concern:

Be it known that I, RICHARD FINCKEN, a citizen of the United States, residing at San Francisco, in the county of San Francisco and State of California, have invented new and useful Improvements in Beer-Cooling Devices, of which the following is a specification.

My invention relates to means for keeping keg-beer cool.

It consists of the parts and the construction and combination of parts, as hereinafter more fully described and claimed, having reference to the accompanying drawings, in which—

Figure 1 is a vertical longitudinal section of my invention. Fig. 2 is a section on line X X of Fig. 1. Figs. 3 and 4 are sections showing modifications of my invention. Fig. 5 is an end view of an ordinary faucet-valve. Fig. 6 is a perspective view of the end of the faucet.

A represents a beer-faucet of ordinary construction, except that it has a reduced portion *a* for the purpose hereinafter stated. These faucets are usually about fifteen inches long, and the mechanism for supporting the end of the faucet and which carries the valve has heretofore been very short, only an inch or two in length, just so as to pass through the head of the keg. This construction did not offer sufficient support for the faucet to allow anything to be hung or supported on the faucet. In attaching a beer-cooler of the construction shown in my Patent No. 788,795, issued to me May 2, 1905, it is essential that the faucet be surrounded by the cooler. In consequence more or less strain is put on the faucet, which is liable to cause a leak if not more serious damage. Besides, the beer that is actually chilled is only that contained immediately in the body of the faucet. If there is a heavy demand on the keg, there is hardly time for the liquid to become sufficiently chilled while flowing through the faucet, since for various reasons it is impractical to make a cooler deep enough to envelop these long faucets their entire length. These faucets are usually provided with a key in the end, as shown at 3, and a bayonet-locking device, as 4, to fit a corresponding socket-piece which is screwed into the keg. As before stated, however, the faucet does not penetrate more than an inch or so into the keg, and by far the greater length of the faucet is outside the keg and entirely unsup-

ported. I have devised a means whereby to employ the same sort of securing, locking, and valve means for the faucet, but to have a considerable length of the faucet projecting 50 into the body of beer in the keg or barrel and less of the faucet outside the keg, to inclose the faucet with a chilling medium, and to circulate this medium around that portion of the faucet within the keg. For this purpose 65 I employ a sleeve, as 5, which is six or eight inches, more or less, in length and of a bore sufficient to easily accommodate the faucet A. The exterior of the sleeve is threaded to permit it to be received into a hole in the 70 head of a beer keg or barrel when properly engaged by a spanner-wrench or other suitable tool. The inner end of the sleeve is supplied with the usual ports 6, the rotatable valve 7, having the stem 8, and with the 75 grooves 9. When the faucet is inserted into the sleeve and the projections 4 engaged bayonet-lock fashion with the grooves 9 and the key 3 engaged with the stem 8 and the faucet turned, the valve 7 is opened to allow the 80 contents of the keg to pass into the faucet, the withdrawals from the keg being controlled by the cock of the faucet.

The reduced portion *a* of the faucet when the latter is in position in the sleeve is contained entirely within the sleeve, and the adjacent end of the enlargement of the faucet just slips into the sleeve and has a reasonably snug fit to provide a suitable support for the middle of the faucet. 90

Between the reduced portion *a* of the faucet and the inside of the sleeve an annular space 10 is formed, which extends into and is surrounded by a considerable body of beer in the keg. This space forms a cooling-jacket 95 when filled with ice-water or other cooling medium, and the cold penetrates not only inwardly to the liquid in the faucet, but outward to the beer in the keg or barrel.

11 represents a cooler which is adapted to 100 fit snug against the head B of the keg and to be secured thereto by any suitable means. If desired, the cooler may be jacketed and the jacket-space filled with suitable non-conducting material, as charcoal, sawdust, 105 cork, &c.

The container differs from that of my patent mentioned in that the present one is designed to be secured to the keg first. Then the faucet is inserted through a cylinder portion 12, 110 which is fixed in the heads of the cooler and open at the ends and is adapted to register

when the cooler is in position on the keg with the sleeve 5, the latter having previously been screwed into the keg.

The cylinder part 12 is slotted, as at 13, or 5 otherwise open to the interior of the cooler, so that the water from the melting ice can pass into the part 12 and surround the faucet when the latter is in position. To prevent leak around the outer end of the faucet, the 10 adjacent side of the cylinder 12 has the internally-projecting annular packing-ring 14 of soft rubber or the like. This packing-ring is held in an annular groove or channel and has such a snug fit within this groove when 15 pressed with the faucet as to prevent any leak at that point.

Suitably interposed between the end of sleeve 5 and the back of the collar around the rear end of the cylinder 12 is a packing-ring 20 15, and the cooler is so attached to the keg and the adjustments are such that no leak will occur at this point, although the space 10 and the interior of the cooler will be in communication. If desired, the packing 15 may 25 be carried permanently by the cooler and adapted to seat in an annular groove 16 in the end of the sleeve 5.

Water from the cooler may be drawn off from time to time through the cock 17. Ice 30 is admitted to the cooler through an opening at the top, closed by the lid or cover 18.

In operation the sleeve 5 is first screwed into a keg clear up to its head. The cooler 11 is then attached to the keg, with the opening 35 for the faucet in the cooler registering with the bore of the sleeve and the packing 15 in place to form a tight joint between the parts. The faucet is then inserted through the cooler and into the sleeve, locked into the 40 latter, and the valve 7 opened. Only enough of the faucet need project beyond the cooler to allow the cock to be turned. When the cooler is filled with ice and the ice has melted a little, the entire length of the faucet will be 45 surrounded by ice-water, and the ice-water column will extend into the body of beer in the keg. The cold will penetrate in all directions, so that the beer in the keg as well as that in and passing through the faucet will 50 be chilled. The result is that with this contrivance one glass after another of sharp cold beer can be drawn.

Not only is the cold transmitted backward into the keg by the water-jacket, but the beer 55 in the faucet and the metal of the faucet constitute conductors, and even in the absence of the jacket the tendency is for the beer in the keg to be chilled. However, the construction of an internal water-jacket as described is preferred.

In Fig. 3 I have shown a modification in which the cooler 11^a has an imperforate cylindrical extension 12^a of the part 12' to extend into the sleeve 5' and to receive and surround the faucet. A packing 15', carried by

the innermost end of the extension 12^a, and a similar packing 14' at the front of the cooler prevent any leak from the cooler. At the same time the whole length of the faucet is surrounded by a body of ice-water. The 70 sleeve 5 of Fig. 1 and the sleeve 5' of Fig. 3 constitute what is, in effect, an extension of the container, said extension in both instances projecting into the keg and for a substantial distance into the liquid contents 75 thereof.

In Fig. 4 is shown still another modification of the invention in which a faucet of regular construction is employed, except that the outside jacket 12^c, which incloses the inner tube of the faucet, is perforated, as at 13', in that portion which is to be surrounded by the cooler 11^b. The latter has simply two openings at front and rear in axial line with the sleeve when the cooler is on the keg and 80 has the packing-rings 14^a 14^b. The faucet is inserted through these openings in the cooler and into the sleeve and suitably locked in place, and the packing-rings embrace the jacket on either side of the perforations to 85 prevent any leak from the cooler around the faucet. The cold water, however, entering the perforations envelops the inside tube of the faucet for its entire length.

It is possible that various other modifications in my invention may be made without departing from the principle thereof, and I do not wish to be understood as limiting myself to the specific construction as herein shown and described. 95

Having thus described my invention, what I claim, and desire to secure by Letters Patent, is—

1. The combination with a keg, of a valved sleeve screwing into the keg and projecting a 105 substantial distance into the body of liquid within the keg, a faucet fitting the sleeve so as to leave a space between said faucet and sleeve, and having suitable locking means therewith, and provided with devices for operating the valve in the sleeve, and a container for a suitable refrigerant inclosing the faucet exterior to the sleeve, said sleeve having a passage which is in open communication with the container whereby the cooling 110 medium in the container may penetrate into the portion of the sleeve within the keg. 115

2. The combination with a keg, of a valved sleeve screwing into the keg and projecting a substantial distance into the body of liquid 120 within the keg, a faucet fitting the sleeve so as to leave a space between said faucet and sleeve, and having suitable locking means therewith and provided with devices for operating the valve in the sleeve, a container 125 for a suitable refrigerant inclosing the faucet exterior to the sleeve, said container having openings at the front and back through which the faucet is inserted, means to prevent leak from the container around the faucet. 130

cet, the interior of the container and the space within the sleeve and around the faucet being in communication whereby the cooling medium in the container may penetrate into the portion of the sleeve within the keg.

3. The combination with a keg, of a container for a refrigerant and a tubular extension from said container extending into the keg and for a substantial distance into the liquid contents thereof, a faucet passing through the container and having a portion extending substantially through the extension thereof and of less diameter than said extension whereby the refrigerant circulates around the extended portion of the faucet within said container extension, a valve at the inner end of the container extension to control the admission of liquid to the faucet, and means for operating the valve.

4. A beer-cooling device comprising an exteriorly-threaded sleeve having a valve at its inner end, a faucet fitting the sleeve so as to leave a space between said faucet and sleeve and provided with means to operate the valve and to lock the faucet in the sleeve, a container for a refrigerant to encircle the exposed portion of the faucet, said container having a slotted lower portion to enable the cooling liquid to circulate between the container and faucet and in the space within the sleeve around the faucet.

In testimony whereof I have hereunto set my hand in presence of two subscribing witnesses.

RICHARD FINCKEN.
